MULTISTAGE FILTER

Ludwig W. Blau, Houston, Tex., assignor to
Standard Oil Development Company, a corpora-
tion of Delaware

Application June 14, 1934, Serial No. 730,565

10 Claims. (Cl. 178—44)

This invention relates to improvements in a multi-stage filter.

It has been known how to combine electric networks so as to render them frequency selective; thus it is possible to make low pass filters, high pass filters or intermediate pass filters. Such a filter is the subject of applicant's pending application U. S. Serial No. 659,822, entitled "Method and apparatus for eliminating low frequencies", filed May 6, 1933.

When filters are to be included in electrical recording systems where high accuracy is required, it becomes necessary to damp out all oscillations originating in the filter itself. This is done successfully in the filter which is the subject of the above mentioned patent application. However, the introduction of damping renders the cut-off of the filter less sharp so that more stages must be added to make up for it. This means that the filter becomes larger and more expensive to construct. The invention which is the subject of this application permits of building a damped filter of a few stages with a sharp cut-off heretofore obtained only by using many stages.

The invention will be fully understood from the following description taken in connection with the accompanying drawing in which latter—

Fig. 1 is a diagrammatic representation of a preferred form of circuit;

Fig. 2 is a diagrammatic representation of a modified form of circuit, and

Fig. 3 is a diagrammatic representation of an arrangement of apparatus for use in reflection shooting.

Referring particularly to Fig. 1 of the drawing, reference numeral 1 designates an input impedance and numeral 2 designates an output impedance. An electric circuit connects the impedances. A plurality of groups of stages of parallel branches 4, 5 and 6 are provided in the circuit. Each group or stage includes a branch A having an inductance 9, a condenser 10 and a resistance 11 of a choke coil. Each group or stage also includes a branch B having a resistance 13 and a condenser 14 connected in series. A condenser 16 is provided in the circuit between the resistance 1 and the branch A of the stage 4, and a condenser 17 is provided in the circuit between the branch B of the stage 6 and the output resistance 2. A damping resistance 19 and a condenser 20 are connected in series in the circuit between the adjoining stages 4 and 5. A damping resistance 21 and a condenser 22 are dis-

posed in the circuit between the adjoining stages 5 and 6.

The circuit operates as follows: Such values of the inductance 9 and condenser 10 of the branch 4 are selected that the combination resonates at, for example, five cycles. The combination of inductance 9 and condenser 10 in series and condenser 14 in parallel are tuned to resonate at, for example, approximately 30 cycles. Then at a frequency of five cycles the voltage across the inductance 9 and condenser 10 in series will be zero. In other words, any frequency of five cycles impressed upon the input resistance 1 will be practically eliminated by the branch A. On the other hand, at 30 cycles the inductance 9 and condenser 10 in series will resonate with the condenser 14 in parallel, and the voltage transmitted across the combination of branches A and B will therefore be very high. This combination of elements results in passing the waves of 30 cycle frequency impressed upon the input resistance 1 practically without attenuation through stage 4.

Referring to stage 5, the inductance 9 and condenser 10 in series are tuned to resonate at, for example, 10 cycles. The combination of inductance 9 and condenser 10 in series of branch A together with the inductance 14 in parallel of branch B is tuned to resonate at 30 cycles. Then any 10 cycle frequency impressed upon the input resistor 1 will set up practically zero voltage across the inductance 9 and condenser 10 of stage 5. In other words, any frequency of 10 cycles impressed upon the input resistance 1 will be practically eliminated in branch A of stage 5. At 30 cycles the inductance 9 and condenser 10 in series of branch A of stage 5 will resonate with the condenser 14 in parallel of branch B and the voltage across this combination will therefore be very high. This stage will therefore pass a frequency of 30 cycles practically without attenuation.

The third stage, designated 6, comprising an inductance 9 and a condenser 10 in series in branch A of this stage may be tuned to resonate at, for example, 15 cycles, while the parallel combination comprising inductance 9 and condenser 10 in series of stage 6 due to an impressed frequency upon the resistor 1 of 15 cycles will be practically zero, so that any 15 cycle frequency will be practically eliminated. On the other hand, since the parallel combination tunes at 30 cycles, any frequency of 30 cycles impressed upon the input resistor 1 will set up a high voltage across the combination and will therefore be 55

transmitted practically without attenuation. While the filter has been described as a three stage filter, it will be understood that there may be any number of stages in the filter.

5 Fig. 2 shows a variation in the circuit illustrated in Fig. 1 and like parts are indicated by like reference numerals. In this circuit reference numeral 24 designates an input transformer and 25 designates an output transformer. The 10 stages of branches 4, 5 and 6 are connected in parallel across the circuit. Each stage comprises the parallel branches A and B as previously described.

Referring particularly to Fig. 3, a preferred 15 arrangement of apparatus for reflection shooting is shown in which reference numeral 28 designates the coil of a magneto-electrical seismograph such as is described in the copending application Serial No. 626,132 of Ludwig W. 20 Blau et al, entitled "Seismograph", filed July 29, 1932. The coil 28 is connected across the grid and filament of a vacuum tube 29 which may be a three electrode or screen grid tube. The vacuum tube 29 is connected to the input 25 resistance 1 of the circuit previously described in connection with Fig. 1. The output resistance 2 of the circuit is connected to a vacuum tube amplifier 30 which in turn is connected to an oscillograph 31 which records the seismograms. 30 Preferably the filter circuit is connected ahead of the amplifier 30 so that the objectionable low frequencies can be eliminated before being amplified.

In the circuits described, the resistances 13 in 35 branch B of each stage of the filter function to damp out oscillations set up in the parallel combination formed by the two branches A and B of each stage. Without the resistors 13 obnoxious oscillations originating in the respective 40 stages would appear in the form of voltages across the output resistor and would therefore be passed on. This would be detrimental to the quality of the seismogram since great care must always be taken to record the filtered earth motion as faithfully as possible and to have no extraneous frequencies on the seismogram originating in the filter or any other parts of the seismograph apparatus. These extraneous frequencies would lead to misinterpretations of the 50 results.

The resistors 19 and 21 are likewise damping resistors designed to damp out oscillations of the following circuits. The resistor 19 damps out oscillations in the circuit consisting of inductance 9 and condenser 10 of branch A of stage 55 4, condenser 10 and inductance 9 of branch A of stage B, and condenser 20 which lies between these stages. The resistor 19 also damps out oscillations in the circuit which comprises inductance 9 and condenser 10 of branch A of stage 60 5, the condenser 14 of branch B of stage 4 and the condenser 20. The resistor 19 also damps out oscillations in the circuit comprising inductance 9 and condenser 10 of branch A of stage 65 4, condenser 14 of branch B of stage 5 and condenser 20. The damping resistor 21 damps out oscillations in the circuit comprising inductance 9 and condenser 10 of branch A of stage 5, condenser 10 of branch A of stage 6 and condenser 22. The resistance 21 damps out also 70 oscillations in the circuit comprising inductance 9 and condenser 10 of branch A of stage 5, the condenser 14 of branch B of stage 6 and condenser 22. The resistor 21 damps out oscillations in the circuit comprising condenser 14 of 75

branch B of stage 5, inductance 9 and condenser 10 of branch A of stage 6 and condenser 22. The input resistor 1 damps out oscillations originating in the circuit comprising the condensers 16 and 10 in the inductance 9. The output resistor 2 damps out oscillations originating in the circuit comprising the condenser 17 and the inductance 13 and condenser 14 of branch B of stage 6.

By reason of the parallel combination of 10 branches as described which may be arranged to tune at any predetermined frequency, which in the case described has been assumed to be 30 cycles, this filter will pass all or practically all energy impressed upon the input with frequency equal to or greater than 30 cycles. The filter here described therefore has a much sharper cut-off with a smaller number of stages than has heretofore been possible to attain. This filter renders possible the practically complete 20 elimination of all frequencies below any certain predetermined cut-off frequency, while passing all energy or practically all energy of frequency higher than the cut-off frequency which is impressed upon the input resistance 1 or the transformer 24.

Various changes may be made within the scope of the appended claims in which it is desired to claim all novelty inherent in the invention as broadly as the prior art permits.

I claim:

1. A filter, comprising an electric circuit having a plurality of stages, each stage including a branch having a condenser and an inductance connected in series and tuned to a given frequency, the corresponding branch of each stage being tuned to different frequencies whereby these frequencies are eliminated, each stage including a branch having a condenser, the two branches of each stage being tuned to resonate together at a given frequency whereby this frequency is passed through the filter.

2. A filter, comprising an electric circuit having a plurality of stages, each stage including a branch having a condenser and an inductance connected in series and tuned to resonate at a given frequency, the corresponding branch of each stage being tuned to different frequencies whereby these frequencies are eliminated, each stage including a branch having a condenser, the two branches of each stage being tuned to resonate together at the same frequency outside of the range of the first mentioned frequencies whereby this frequency is passed through the filter.

3. A filter, comprising an electric circuit having a plurality of stages, each stage including a branch having a condenser and an inductance connected in series and tuned to resonate at a given frequency, the corresponding branch of each stage being tuned to different frequencies whereby these frequencies are eliminated, each stage including a branch having a condenser, the two branches of each stage being tuned to resonate together at the same frequency outside of the range of the first mentioned frequencies whereby this frequency is passed through the circuit and a damping resistance in the circuit between adjoining stages for damping out the natural frequencies of the filter.

4. A filter, comprising an electric circuit having a plurality of stages, each stage including a branch having a condenser, an inductance and a resistance connected in series and tuned to a given frequency, the corresponding branch of

each stage being tuned to different frequencies whereby these frequencies are eliminated, each stage including a branch having a condenser and a resistance connected in series, the two branches of each stage being tuned to resonate together at a given frequency outside of the range of the first mentioned frequencies whereby this frequency is passed by the filter, and a damping resistance in the circuit between adjoining stages for damping out the natural frequencies of the filter.

5 5. A filter, comprising an electric circuit having a plurality of stages, each stage including a branch having a condenser and an inductance and a resistance connected in series and tuned to a given frequency, the corresponding branch of each stage being tuned to different frequencies, each stage including a branch having a condenser and a resistance connected in series, the two branches of each stage being tuned to resonate together at a given frequency, and a damping resistance for damping out the natural frequencies of the filter and a condenser in the circuit between adjoining stages.

10 6. A filter, comprising an electric circuit having a plurality of stages, each stage including a first shunt arm having a condenser, an inductance and a resistance connected in series, and a second shunt arm having a condenser connected in parallel with the first shunt arm, the first shunt arm of each stage being tuned to different low frequencies whereby these low frequencies are eliminated, the second shunt arm of each stage being tuned with respect to the first shunt arm of that stage to resonate at higher frequencies whereby the higher frequencies are passed.

15 7. A filter for eliminating low frequency waves, comprising the inductance coil of a seismograph connected across the grid and filament of a vacuum tube, an input impedance connected to the plate resistor of the vacuum tube, an output impedance, an electric circuit connecting the impedances and including a plurality of stages of parallel shunt arms, each stage including a first shunt arm having a condenser, an inductance and a resistance connected in series and a second shunt arm having a condenser connected in parallel with the first shunt arm, the first shunt arm of each stage being tuned to different low frequencies whereby these low frequencies are eliminated, the second shunt arm of each stage being tuned with respect to the first shunt arm of that stage to resonate at higher frequencies whereby the higher frequencies are passed, a vacuum tube amplifier connected to the output impedance, and an oscillograph connected to the amplifier.

20 8. A filter for eliminating low frequency waves, comprising the inductance coil of a seismograph connected across the grid and filament of a vacuum tube, an input impedance connected to the plate resistor of the vacuum tube, an output impedance, an electric circuit connecting the impedances and including a plurality of stages, each stage including a branch having a condenser and an inductance and a resistance connected in

series and tuned to a given frequency, the corresponding branch of each stage being tuned to different frequencies, each stage including a branch having a condenser and a resistance connected in series, the two branches of each stage being tuned to resonate together at a given frequency, a damping resistance for damping out the natural frequencies of the filter and a condenser in the circuit between adjoining stages, a vacuum tube amplifier connected to the output impedance and an oscillograph connected to the amplifier.

25 9. A filter for eliminating low frequency waves, comprising the inductance coil of a seismograph connected across the grid and filament of a vacuum tube, an input impedance connected to the plate resistor of the vacuum tube, an output impedance, an electric circuit connecting the impedances and including a plurality of stages of parallel shunt arms, each stage including a first shunt arm having a condenser, an inductance and a resistance connected in series and a second shunt arm having a condenser and a resistance in series, the latter shunt arm being connected in parallel with the first shunt arm, the first shunt arm of each stage being tuned to different low frequencies whereby these low frequencies are eliminated, the second shunt arm of each stage being tuned respectively to the first shunt arm of that stage to resonate at higher frequencies whereby the higher frequencies are passed, a condenser connected between the input impedance and the first shunt arm, a condenser connected between the last shunt arm and the output impedance, a vacuum tube amplifier connected to the output impedance and an oscillograph connected to the amplifier.

30 10. A filter for eliminating low frequency waves, comprising the inductance coil of a seismograph connected across the grid and filament of a vacuum tube, an input impedance connected to the plate resistor of the vacuum tube, an output impedance, an electric circuit connecting the impedances and including a plurality of stages of parallel shunt arms, each stage including a first shunt arm having a condenser and inductance and a resistance connected in series and a second shunt arm having a condenser and resistance connected in series, the latter shunt arm being connected in parallel with the first shunt arm, the first shunt arm of each stage being tuned to different low frequencies whereby these low frequencies are eliminated, the second shunt arm of each stage being tuned with respect to the first shunt arm of that stage to resonate at higher frequencies whereby the higher frequencies are passed, a condenser and resistance in series connected between the input impedance and the first shunt arm, a condenser and resistance in series connected between the last shunt arm and the output impedance, a vacuum tube amplifier connected to the output impedance, and an oscillograph connected to the amplifier.
